UNITED STATES PATENT OFFICE.

WILLIAM WALLACE KEMP AND WILLIAM H. VAN HORN, OF BALTIMORE, MARYLAND.

GAS-BURNER.

1,185,205.

Specification of Letters Patent.

Patented May 30, 1916.

Application filed February 20, 1915. Serial No. 9,598.

To all whom it may concern:

Be it known that we, WILLIAM W. KEMP and WILLIAM H. VAN HORN, citizens of the United States, residing at Baltimore, in 5 the State of Maryland, have invented new and useful Improvements in Gas-Burners, of which the following is a specification.

This invention relates to gas burners, and has for an object to provide a burner 10 with a plurality of burner tips arranged radially and circumferentially around the body of the burner to provide for a substantially cylindrical heater or burner for various uses where intense heat is required, 15 and where it is desired to heat a surrounding or inclosing wall or receptacle.

Another object of this invention is to provide a burner of this type which is so peculiarly constructed and formed that it may 20 be cast with the burner tips integral with the body thereof, and wherein the various bores and counterbores required for controlling the passage of gas may be quickly and easily formed in the casting, and where- 25 in distributing or controlling disks, herein-after more specifically referred to, may be readily applied to the tips of the casting.

With these and other objects in view the above and other objects will be more clearly 30 described and pointed out in the following detail description of the present preferred embodiment of this invention, the same being shown in the accompanying drawings wherein,—

Figure 1 is a side elevation of a burner constructed according to this invention, one 35 end of the same being shown in section. Fig. 2 is a transverse section of the burner taken through the opposed tips. Fig. 3 is a longitudinal section of one end of the burner, showing a slightly modified form 40 wherein the end caps are detachable from the body of the casting. Fig. 4 is an end elevation of the same. Fig. 5 is a side elevation of one end of the burner, showing a modified arrangement of the burner tips 45 about the body of the casting. Fig. 6 is a transverse section through the same. Fig. 7 is a fragmentary longitudinal sectional view 50 of another modified form of the burner. Fig. 8 is a transverse section through the same.

Referring to these drawings, wherein like numerals indicate similar parts throughout 55 the several views, 10 designates the body

of the burner, shown in Fig. 1 as comprising a single casting provided with a centrally disposed supply passage or opening 11. The body 10 has, arranged in longitudinal rows in the sides thereof, cylindrical projections or bosses 12 radiating from the supply passage 11. The bosses 12 are spaced apart slightly, and the casting or body 10 is provided with an annular chamber 13 extending from end to end of 60 the casting, and through which the bosses 12 extend so that each boss 12 is surrounded by the chamber 13, as may be clearly seen from Figs. 1 and 2.

Each boss 12 is hollow or has a bore of 70 relatively large diameter therein, forming a gas receiving chamber 14 of the full depth of the boss and opening through the outer end thereof. Each boss 12 has in its inner end a relatively small opening or perforation 15 establishing communication between the central supply passage 11 and the gas receiving chamber 14 of the boss or tip. A distributing disk 16 is fitted in the outer end of each boss or tip 12, the disk 75 16 having a plurality of radiating slots opening through the edge of the disk, as shown in Fig. 5, to thus break up the gas in the chamber 14 into a plurality of separate radiating films or sheets to thus insure the mixing of the surrounding air with the gas, and to thus provide for the more complete combustion of the gas and a consequent increase in the intensity of the 80 heat of the flame.

From Fig. 1 it will be noted that the end of the casting has openings, the opening 17 being the gas inlet communicating with the central gas supply and being offset therefrom, while the opening 18 leads 90 directly into the annular jacket or chamber 13. The openings 17 and 18 are internally screw threaded, or given any other suitable form, to respectively receive gas and water supply pipes to feed gas to the burner tips 12 and water to the jacket 13. The opposite end of the burner may be of similar construction to admit gas at the opposite end and to admit circulation of water 95 through the jacket 13.

The opposite end of the casting is formed in a similar manner with the water and gas openings to admit of the circulation of water through the burner and to admit of the introduction of gas in the opposite end 100 105 110 111

of the burner if desired. The opening not in use being adapted to be plugged in any well known manner.

In Figs. 3 and 4 a slight modification of the burner is shown wherein the casing 10^a terminates at one end in an externally threaded extension 19 to which is detachably secured a cap 20, the latter having internal threads engaging the threaded extension 19. The cap 20 has a laterally offset gas inlet 17^a communicating with the gas supply passage 11, and has a water inlet 18^a communicating with the jacket 13. The openings 17^a and 18^a are suitably formed to receive gas and water supply pipes. The opposite end of the body 10^a is provided with a cap of like form having the same passages or inlets therein, and adapted for the purpose of permitting a complete circulation of the water through the jacket 13 and the feeding of gas into the opposite end of the burner.

As shown in Figs. 5 and 6, the bosses or tips 12^a may be arranged spirally about the body 10, instead of in longitudinal rows as shown in Figs. 1 and 3, and it is understood that any other arrangement of the burner tips or bosses 12 may be had which is found desirable in the manufacture of the burner, and for the various uses to which the burner is applied.

In Figs. 7 and 8 of the drawing there is shown a further modified form of the invention wherein the burner is made up of an inner pipe 11^b and an outer pipe 10^b, the two pipes being concentrically arranged with respect to each other and securely joined or held together by the burner tips 12^b. As shown, these burner tips are externally threaded at their outer and inner ends for engagement respectively through threaded openings formed in the outer pipe 10^b and in the inner pipe 11^b. The tips 12^b are turned down through the registering openings in the pipes to bind the tips in place and to firmly connect the pipes. In all other respects the burner tips 12^b are of the form disclosed in connection with the illustrations above referred to and the tips are used in the present instance in uniting the concentric pipes and holding the same together as a unitary device.

Although the above sets forth a specific

form of this invention, it is understood that various changes may be made in the arrangement of the burner tips, the form of the casting, and the application of the caps to the ends of the burner, without departing from the spirit of the invention, such changes and modifications being limited only by the scope of the following claims.

What is claimed is—

1. A burner comprising an inner gas supply tube, an outer tube surrounding the first supply tube to form a water-jacket thereabout, tips extending radially from the inner tube through the outer tube, said burner having at one end thereof an offset passage for said centrally disposed gas passage, and a passage outside of said first offset passage communicating with the water chamber.

2. A burner comprising an inner gas supply tube, an outer tube surrounding the supply tube to form a water-jacket thereabout, tips extending radially from the inner tube through the outer tube, and a cap removably connected to the ends of said tubes and having a passage extending through the end wall of the cap communicating with said gas supply tube, said cap also having a second passage opening through the end wall of said cap and located outside of said first opening and communicating with the water-jacket.

3. A burner comprising an inner gas supply tube, an outer tube surrounding the first supply tube to form a water-jacket thereabout, tips extending from the inner tube through the outer tube, the ends of said tubes being screw-threaded, and a cap having an offset passage communicating with the inner tube, and a passage communicating with the water-jacket, the cap having internal screw-threads at the inner ends of said passages adapted to receive the screw-threaded ends of said tubes.

In testimony whereof we have hereunto set our hands in presence of two subscribing witnesses.

WILLIAM WALLACE KEMP.
WILLIAM H. VAN HORN.
